UNITED STATES PATENT OFFICE.

ANTON M. OPSAL, OF MINNEAPOLIS, MINNESOTA.

MOTION CONTROL FOR ARTIFICIAL LIMBS.

1,413,054.

Specification of Letters Patent. Patented Apr. 18, 1922.

Application filed July 9, 1921. Serial No. 483,526.

To all whom it may concern:

Be it known that I, ANTON M. OPSAL, a citizen of the United States, residing at Minneapolis, in the county of Hennepin and State of Minnesota, have invented certain new and useful Improvements in Motion Controls for Artificial Limbs; and I do hereby declare the following to be a full, clear, and exact description of the invention, such as will enable others skilled in the art to which it appertains to make and use the same.

My invention has for its object to provide an extremely simple and highly efficient motion control for artificial thigh limbs, and to this end it consists of the novel devices and combinations of devices hereinafter described and defined in the claims.

In the accompanying drawings, which illustrate the invention, like characters indicate like parts throughout the several views.

Referring to the drawings:

Fig. 1 is a front view of a man having a thigh amputation to which is applied an artificial limb held in position by the improved motion control;

Fig. 2 is a view in front elevation of the artificial limb and motion control on an enlarged scale, some parts being broken away;

Fig. 3 is a side view of the parts shown in Fig. 2;

Fig. 4 is a rear view of the parts shown in Figs. 2 and 3;

Fig. 5 is a fragmentary detail view showing the way the straps are connected to the upper leg section; and

Fig. 6 is a perspective view of one of the strap-connecting links.

The numeral 7 indicates a man having a right thigh amputation to which is applied an artificial thigh limb comprising upper and lower leg sections 8 and 9, respectively, connected by a knee joint 10.

The improved motion control includes a pair of flat relatively wide straps connected for a short distance at their adjacent edges to afford an intermediate section 11, which extends over the upper leg section 8 at the knee joint 10. The straps, below the intermediate section 11, afford relatively short diverging sections 12 and said straps, above the intermediate section 11, afford relatively long diverging sections 13.

The strap sections 12 are adjustably attached to opposite sides of the lower leg section 9, in front of a vertical line intersecting

the axis of the knee joint 10, by forming therein a plurality of vertically spaced button-hole-like apertures 14 adapted to receive headed studs 15 secured to said lower leg section. The strap sections 13 extend loosely through fixed loop guides 16 on the lower ends of relatively short elastic straps 17 and from thence said strap sections extend downward in diverging relation and are adjustably attached to opposite sides of the upper leg section by fixed loop guides 18. These loop guides 18 are located just above the knee joint 10 and back of a vertical line which intersects the axis of said joint.

The strap sections 13 are extended through the loop guides 18, folded upon themselves and adjustably connected to vary the operative length of the strap connections between the upper and lower leg sections by headed links 19, which may be inserted through any pair of a plurality of holes 20 in each of said straps, (see Fig. 5).

The elastic straps 17 are attached to a pair of suspenders 21 crossed and connected at the back and arranged to be extended over the shoulders and under the arms of the wearer and the ends thereof connected and attached to the upper ends of the elastic straps 17.

To hold the thigh limb 8-9 in place when the wearer is sitting down, there is provided a strap 22 having at its upper end an elastic section 23, the upper end of which is attached, as shown, to the suspenders 21 where they are crossed at the back. The lower end of the strap 22 is extended through a fixed loop guide 24 secured to the back of the upper leg section 8 slightly above the loop guides 18, folded upon itself and adjustably connected by one of the links 19 in the same manner that the strap sections 13 are adjustably connected. This strap connection 22-23 is of such length as to be entirely out of action when the wearer is walking, but immediately becomes active to hold the thigh limb 8-9 in position when the wearer starts to sit down and while he is sitting down.

The primary idea of the invention is to provide a motion control that is not only extremely simple and comfortable to wear, but that will give to an artificial thigh limb a natural swinging movement. The very action of the wearer in carrying his shoulders forward in preparing to take a step places the short elastic straps 17 under ten-

sion so that when the thigh limb is lifted from the ground, said elastic straps will give muscular locomotion to said thigh limb, or, in other words, said elastic straps 5 will pick the thigh limb up and give the same knee action and a free and easy forward swinging movement. The improved motion control permits the use of relatively wide flat straps, which are free for longitudinal movement in the loop guides 18.

In making my motion control, I have endeavored to eliminate all objectionable features in other motion control devices, such as pulleys, round and narrow straps and use 15 of sash cords. The intermediate strap section 11 frictionally engages the upper leg section 8, at the knee joint 10, and controls the movement of the lower leg section. By adjusting the strap sections 12 on the headed 20 studs 15, the intermediate strap section 11 may be raised or lowered, in respect to the knee joint 10, to vary the frictional engagement between said intermediate strap section and the upper leg section, so that the 25 lower leg section 9 may be caused to bend easily or hard to suit the wearer. The improved motion control is designed to relieve the wearer of all drawing action produced by the suspenders, under the action of the 30 elastic straps 17, while he is sitting down.

What I claim is:

1. The combination with upper and lower leg sections connected by a knee joint, of a motion control including strap guides supported from the wearer, and a pair of straps 35 connected over the knee and having one of their ends attached to the lower leg section and having their other ends attached to the upper leg section and arranged to run over 40 the strap guides.

2. The combination with upper and lower leg sections connected by a knee joint, of a motion control including relatively short elastic straps supported from the wearer 45 and having strap guides, and a pair of straps connected over the knee and having one of their ends attached to the lower leg section and having their other ends attached to the upper leg section and 50 arranged to run over the strap guides.

3. The combination with upper and lower leg sections connected by a knee joint, of a motion control including relatively short elastic straps supported from the wearer 55 and having strap guides, and a pair of straps connected over the knee and having one of their ends attached to the lower leg section and having their other ends attached to the upper leg section and arranged to run 60 over the strap guides, the several ends of the straps being adjustably attached.

4. The combination with upper and lower leg sections connected by a knee joint, of a motion control including strap guides adapted to be supported from the wearer, a pair 65 of straps connected at the knee, said straps below the knee being in diverging relation and attached to the sides of the lower leg section, said straps above the knee being in diverging relation and extending through 70 the strap guides and attached to the upper leg section, the points at which the straps are attached to the upper and lower leg sections being, respectively, forwardly and rearwardly of a vertical line that intersects 75 the axis of the knee joint.

5. The combination with upper and lower leg sections connected by a knee joint, of a motion control including relatively short elastic straps adapted to be supported from 80 the wearer and having strap guides, a pair of straps connected to afford an intermediate section arranged to frictionally engage the upper leg section over the knee, the strap sections below said intermediate strap section being in diverging relation and attached to the sides of the lower leg section at the front thereof and the straps above said intermediate strap section being in diverging 85 relation and attached to the sides of the 90 upper leg section at the back thereof and extending through said strap guides.

6. The combination with upper and lower leg sections connected by a knee joint, of a motion control including a pair of suspenders with connections to the leg sections, and a connection including an elastic section 95 between the suspenders and the upper leg section at the back thereof.

7. The combination with upper and lower 100 leg sections connected by a knee joint, of a motion control including strap guides supported from the wearer, and a pair of straps attached at one of their ends to the lower leg section and at their other ends to the upper leg section, directed over the knee and arranged to run over the strap guides, said strap guides being arranged to release the pull on the straps when the wearer sits down.

8. The combination with upper and lower 105 leg sections connected by a knee joint, of a motion control including elastic straps supported from the wearer and having strap guides, and a pair of straps attached at one of their ends to the lower leg section and at 110 their other ends to the upper leg section, directed over the knee and arranged to run over the strap guides, said strap guides being arranged to release the pull on the straps when the wearer sits down.

In testimony whereof I affix my signature.
ANTON M. OPSAL
